UNITED STATES PATENT OFFICE.

ALFRED B. FOWLER, OF CENTRAL FALLS, RHODE ISLAND, ASSIGNOR, BY MESNE ASSIGNMENTS, TO UNITED SHOE MACHINERY COMPANY, OF PATERSON, NEW JERSEY, A CORPORATION OF NEW JERSEY.

CHANNELING-MACHINE.

SPECIFICATION forming part of Letters Patent No. 707,576, dated August 26, 1902.

Application filed June 19, 1897. Serial No. 641,405. (No model.)

To all whom it may concern:

Be it known that I, ALFRED B. FOWLER, of Central Falls, in the county of Providence and State of Rhode Island, have invented certain 5 new and useful Improvements in Channeling-Machines for Boots and Shoes, of which the following, taken in connection with the accompanying drawings, is a specification.

The present invention relates to improvements in machines for channeling the soles of boots and shoes commonly termed "channeling-machines." As I am advised of the art, the term "channeling-machines" includes machines used for channeling either insoles 10 or outsoles, both operations comprising the making of an incision in the sole and the turning up of a portion thereof to form a lip or channel-flap. In the case of outsoles the turned-up portion of the sole is turned down 15 again over the channel after the seam has been sewed therein to cover and protect the seam and is commonly called the "channel-flap," while in insoles the turned-up portion is frequently used to receive the seam either 20 with or without suitable reinforcement and is commonly called a "lip." The term "lip" is, however, sometimes applied to the turned-up portion of the sole in the case of outsoles as well as insoles and is so used in this specification. 25

Prior to my present invention it has been the practice to form the channel in boot or shoe soles by machines embodying a stationary knife or a knife which vibrates in the 30 line of feed. The objection to machines of the stationary-knife type has been found to be that in the process of cutting the channel the lip becomes wrinkled or puckered, which is very objectionable either in case of an insole or an outsole, and, further, great power is required to operate the machine. These difficulties were to some extent obviated by the provision in prior machines of a knife vibrating in the line of feed; but such prior machines have failed to fully overcome these 35 difficulties, because the cutting action of the vibrating knife is directly opposed to the feed—that is to say, the impact of the edge of the knife when brought by the action of

its vibrating mechanism against the work 50 tends to force the work back in a direction opposite to that in which it is being carried by the feed.

The object of the present invention is to obviate the objections to the stationary-knife 55 machines more fully than has been heretofore done by machines of the vibrating-knife type; and to this end it consists in providing in a channeling-machine a vibrating channeling-knife which is arranged to cut transversely to the line of feed and obliquely to the surface of the work, and thereby form 60 the usual continuous channel and lip. The extent of the vibrating movements imparted to the knife is preferably not sufficient 65 to withdraw the knife completely from the work, and in order to enable the knife to cut a channel when so operated I provide my vibrating channeling-knife with a cutting edge, a portion of which is at an angle to the line 70 of feed.

In channeling-machines of the prior art it has been proposed to use both a continuous and an intermittent feed. To secure the most perfect operation of my improved machine to 75 cut a smooth channel and leave a continuous even lip, I prefer to use a continuous feed and to provide my vibrating channeling-knife with a cutting edge, against which the work is forced by the action of the feed. Since the 80 knife is arranged to cut transversely to the line of feed, the combined feeding movement of the work and the movement of the knife gives a shear cut, which insures a smooth and unwrinkled lip and easy operation of the machine, the cutting action of the knife having practically no tendency to prevent the feed of the work. To still further decrease the tendency of the cutting action of the knife to prevent the feeding of the work, a portion of 85 the cutting edge of the knife is preferably arranged obliquely to the surface of the work, so that the knife frees the work during its backward movement and performs the principal part, if not the whole, of the cutting operation during its forward stroke. On account of the easy operation of the machine feeding mechanism which lightly engages the 90 95

work may be employed and certainty of operation without injury or defacement of the work secured.

While I consider the construction and arrangement of parts above referred to as securing the most perfect results and of value for the reasons above stated, it is to be understood that my invention considered in its broadest sense is not limited thereto, but that these constructions and arrangements of parts embody my invention in its preferred form only.

In the preparation of both outsoles and insoles to adapt them to receive the stitches of the seam which unite them to the other portions of the shoe the lip formed by the channel-knife must be turned up in order to open the channel for the reception of the stitches. In order to turn up the lip, a feature of my invention consists in providing a channeling-machine comprising a vibrating channeling-knife, with a vibrating lip-turning device following the knife and acting to turn over the lip formed thereby. Preferably this lip-turning device is provided with a working face shaped to turn up the lip when forced against it by the feed, whereby the lip-turning device is rendered capable of operation in a machine provided with means for continuously feeding the work, and a vibrating lip-turning device of this construction I consider a feature of my invention in and of itself when used in a machine provided with means for continuously feeding the work.

Other features of my invention consist in certain devices and combinations of devices hereinafter described and claimed, the advantages of which will be apparent from the description hereinafter contained.

Having thus indicated the nature and scope of my invention, I will now proceed to describe the specific embodiment thereof illustrated in the accompanying drawings, in which—

Figure 1 represents a side elevation, partly in section, of a machine embodying my invention. Fig. 2 represents a horizontal section of the machine on the line A B in Fig. 1. Fig. 3 represents an enlarged detail side elevation of the knife or cutter, a portion of the knife-carrier, and the turning device to open the channel, also a sectional view of a portion of a boot or shoe, showing the action of the knife when channeling the same. Fig. 4 represents a bottom view of the parts shown in Fig. 3 with the exception of the boot or shoe shown in said figure. Fig. 5 represents a front elevation of the parts shown in Fig. 4. Fig. 6 represents a vertical section on the line C D shown in Fig. 3.

Like characters of reference refer to like parts wherever they occur on the different parts of the drawings.

The machine is provided with a suitable frame 2 for the support of the various parts thereof. Within bearings in the frame is mounted the driving-shaft 3, (shown in dotted lines in Fig. 1,) which shaft is rotated in its

bearings by means of the pulley 4, mounted thereon. Upon the shaft 3 is firmly mounted the worm 5, which worm meshes into and rotates the worm-wheel 6, splined upon the horizontal portion 7 of the feed-shaft, which portion of the feed-shaft is mounted in bearings on the frame 2 and is free to move longitudinally within said bearings.

The forward end of the portion 7 of the feed-shaft is mounted within a bearing or bearings in a block 8 and is kept from longitudinal movement within said bearings by means of a shoulder and a collar 9 on said shaft. The block 8 is mounted in guides 10 on the frame 2 in such a manner that it can be moved forward or backward, as desired, but is normally held backward with a yielding pressure by means of the spring 11, which surrounds a rod 12, attached to said block, or it may be held backward by any other suitable and well-known device. This spring is inserted between an ear on the frame and a collar 13 on the rod, which collar is adjustable upon the rod to vary the influence of the spring upon the block. Within bearings on the block 8 is mounted the inclined portion 14 of the feed-shaft, which portion is connected to the portion 7 by means of the universal joint 15 or equivalent device, whereby the rotations of the portion 7 will be conveyed to the portion 14 of the feed-shaft, and as the worm 5 causes a rotation of the portion 7 it will also cause a rotation of the portion 14.

Upon shaft 14 is firmly but removably secured the beveled feed-wheel 16, the periphery of which is so shaped that its serrated surface will be pressed against the projecting edge of the welt 17 of the boot or shoe with a yielding pressure by the action of the spring 11. The feed-wheel is arranged to enter the groove which surrounds the boot or shoe between the welt and the upper 18 and to press against the welt.

The machine is provided with a supporting and antifriction roll 19, which rests against the under surface of the outer sole 20 of the shoe. The roll 19 is loosely mounted upon a block 21, which is movable with said roll up and down within guides in the frame 2 and is preferably normally held at its lower position by means of a spring 22 or an equivalent device, arranged substantially as shown in Fig. 1.

It will be seen that as the shaft 14, with its attached feed-wheel 16, is mounted upon and movable with the block 8 and as said block is held backward with a yielding pressure by the spring 11 the projecting edge of the sole of the boot or shoe will be clamped with a yielding pressure between the roll 19 and the serrated edge of the feed-wheel 16 by means of the spring 11, and therefore any rotation of the feed-wheel will cause a forward movement or a feeding of the boot or shoe. It will also be seen that the longitudinal movement of the feed-shaft 7 and block 8 enables the distance between the feed-wheel 16

and the roll 19 to be adjusted so as to allow for variations in the thicknesses of the soles and welts of different boots and shoes.

A bell-crank or other suitably-shaped lever 5 23 is pivotally attached at 24 to the frame 2, having one end thereof attached to a suitable treadle (not shown in the drawings) by means of the rod 25 and having the opposite end in engagement with the pin or roll 26 on the 10 collar 13 in such a manner that the block 8 can be moved in its guides 10 against the influence of the spring 11 by the operation of the treadle and lever 23 in order to withdraw the feed-wheel 16 from contact with the boot or 15 shoe, so as to allow the removal of the stock from the machine when finished and the placing of other stock in position to be operated upon.

A bell-crank lever 27 is fulcrumed at 28 to 20 the block 21 and is vibrated upon said fulcrum by means of a connecting-rod 29, pivotably but adjustably attached to said lever by means of the bolt 30, and said rod is also pivotally attached to a crank-pin 31 or to an 25 eccentric on the driving-shaft. On the free end of the lever 27 is mounted the channeling knife or cutter 32, provided with the cutting edge 33. This knife is secured to said lever in any suitable manner, as by means of 30 the cap-screw 34, which passes through a slot 35 in the knife, as shown, or it may be secured in any other and well-known equivalent manner, if desired.

As a result of the construction above described it will be seen that the channeling-knife is arranged to cut transversely to the line of feed and obliquely to the surface of the work and will act to form a continuous channel and lip as the work is fed past the 35 knife by the feeding mechanism. As shown in the drawings, the cutting edge 33 of the knife is curved so that a portion thereof extends at an angle to the line of feed and is so arranged that the work is forced against such 40 portion by the action of the feeding mechanism. By arranging and shaping the cutting edge 33 as shown a portion of the edge is oblique to the line of feed, whereby the knife frees the work during its backward stroke 45 and performs the principal part, if not the whole, of its cutting action during its forward stroke. The result of the combined feeding movement of the work and the movement of the knife gives a shear cut, which 50 insures a smooth and unwrinkled lip and offers practically no obstruction to the feeding of the work. By arranging a portion of the cutting edge 33 at an angle to the line of feed the work is freed during the backward 55 stroke of the knife, which still further prevents the knife from offering an obstruction to the feeding of the work.

The vibrating movements imparted to the 60 knife 32 are preferably not sufficient in extent to withdraw the knife completely from the work. In order to vary the amount of vibrations of the knife 32, I provide the ma-

chine with any suitable adjustment, and on the drawings this adjustment has been shown as consisting of the slot 36 within the lever 70 27, within which slot the bolt 30 is adjustable, so as to vary the amount of movement imparted to the lever 27 by the action of the crank-pin 31; but the manner of adjusting said movement may be changed at will, as it 75 forms no essential part of my present invention.

It is desirable that the lip 37 of the channel in the sole should be turned back upon the surface of the sole, so as to open the channel 80 into proper position to receive the stitches, and in order to automatically accomplish this result at the same time that the channel is being formed I provide the machine with an automatic lip-turning device, which is constructed substantially as follows: To the lever 27 is secured the piece 38, having a surface 39, made similar to that of the mold-board of a plow, which surface commences near the cutting edge of the knife and extends backward and downward substantially as shown and in such a manner that as soon as the lip 37 is cut from the sole its free end will commence to gradually move backward and downward as it is fed against the surface 90 39 until it has reached the desired position or has been turned backward against the surface of the sole. The vibrations of the lever 27 are such that it causes the surface 39 to lightly pound the lip 37 into the desired position. The roll 40 is loosely mounted upon 95 the shaft 14, and the edge of the sole of the boot or shoe when fed is held against the periphery of said roll, so as to cause said roll to act as a gage to determine the position 100 of the channel on the sole from the contour of the sole and not from that of the inseam, which would be the case if the roll 40 were dispensed with.

As before stated, the block 21 is movable 110 vertically within guides in the frame 2 and is normally kept in its lowest position by means of the spring 22. A lever 41 is fulcrumed at 42 to the frame 2 and has one end connected to a suitable treadle by means of 115 the rod 43 and has its opposite end connected to the block 21 by means of the pin or link 44 or in any other equivalent manner. It will thus be seen that the block 21, with the attached cutter 32, may be raised against the 120 influence of the spring 22 by the operation of the lever 41, whereby the position of the fulcrum of the channeling-knife lever 27 and the path of movement of the knife may be changed in order to vary the distance of the 125 channel made by said cutter from the edge of the sole. The amount that the block can be raised or lowered, and consequently the two extreme positions which the roll 19 can occupy upon the sole of the boot or shoe in relation to the feed-wheel 16 and the roll 40, is governed and adjusted by means of the lever 130 41. On the drawings the block 21 has been shown as being raised to its upper position

against the influence of the spring 22 by the operation of lever 41. The machine is provided with suitable adjustable stops 45 45 to come into contact with the block 21 or a projection 5 46 on said block in order to limit the up-and-down movements of said block.

As the roll 19 is made adjustable up and down in relation to the feed-wheel 16 and as the feed-wheel is pressed against the welt of 10 the shoe by the action of the spring 11, there would be a tendency of the feed-wheel to cause the shoe to tip toward the cutter when the roll 19 is in its lower positions, and in order to obviate this difficulty I prefer to provide the machine with the rest or presser-foot 47, which is attached to the block 21 and has its upper end resting against the outer sole 20 of the boot or shoe, so as to support the shoe. This rest is preferably forked to 15 receive the cutter when vibrated.

By the use of the inclined portion 14 of the feed-shaft mounted upon the sliding-block 8 and having the feed-wheel mounted on said shaft and provided with a working surface 25 inclined to its axis of rotation I am able to feed the boot or shoe by the periphery of the feed-wheel and by working upon the upper surface of the welt to have said wheel enter the groove on the boot or shoe made at the 30 junction of the upper and welt and to keep the feed-wheel as much as possible from preventing the operator from inspecting the work during the operation of the machine.

Having thus described my invention, I 35 claim as new and desire to secure by Letters Patent of the United States—

1. A channeling-machine, having, in combination, a vibrating channeling-knife arranged to cut transversely to the line of feed 40 and having a portion of its cutting edge oblique to the line of the feed, and means for actuating said knife, substantially as described.

2. A channeling-machine, having, in combination, a vibrating channeling-knife arranged to cut transversely to the line of feed 45 and having a portion of its cutting edge at an angle to the line of feed against which the work is forced by the action of the feed, means for actuating the knife and suitable feeding 50 mechanism, substantially as described.

3. A channeling-machine, having, in combination, mechanism for continuously feeding the work, a vibrating channeling-knife arranged to cut transversely to the line of feed 55 and having a cutting edge against which the work is forced by the action of the feed, and means for actuating the knife, substantially as described.

4. A channeling-machine, having, in combination, a vibrating channeling-knife arranged to cut transversely to the line of feed and obliquely to the surface of the work to 60 form a continuous channel and lip, means for

actuating the knife, and means for feeding the work, substantially as described.

5. A channeling-machine, having, in combination, a vibrating channeling-knife arranged to cut transversely to the line of feed and a lip-turning device in close proximity to and movable with said vibrating channeling-knife, substantially as described.

6. A channeling-machine, having, in combination, a vibrating channeling-knife, a vibrating lip-turning device following said knife to turn over the lip formed thereby, and means for actuating the knife and lip-turning device, substantially as described.

7. A channeling-machine, having, in combination, means for continuously feeding the work, a vibrating lip-turning device provided 80 with a working face shaped to turn up the lip when forced against it by the feed, and means for actuating the lip-turning device, substantially as described.

8. A channeling-machine, having, in combination, a beveled feed-wheel arranged to enter the crease between the upper and welt, and an edge-gage consisting of a wheel mounted concentrically with the feed-wheel, substantially as described.

9. A channeling-machine, having, in combination, an oscillating channeling-knife, a channel-knife lever, and means for moving the fulcrum of the channel-knife lever during the operation of the machine to vary the 95 position of the channel, substantially as described.

10. A channeling-machine, having, in combination, a vibrating channeling-knife arranged to cut transversely to the line of feed, and means for changing the path of movement of the knife during the operation of the machine, substantially as described.

11. A channeling-machine, having, in combination, a channeling-knife and feed mechanism comprising a shaft arranged to slide and rotate, a beveled feed-wheel engaging the crease between the upper and welt rotated by said shaft, means to rotate said shaft, and a spring acting to impart a sliding movement 105 to said shaft and hold the feed-wheel in contact with the welt, substantially as described.

12. A channeling-machine, having, in combination, a vibrating channeling-knife, a vibrating lip-turning device, and means for actuating the knife and lip-turning device, substantially as described.

In testimony whereof I have signed my name to this specification, in the presence of two subscribing witnesses, on this 14th day 120 of May, A. D. 1897.

ALFRED B. FOWLER.
